(57) **CLAIM**

The ornamental design for a combined wet/dry vacuum cleaner with tool caddy and wheels, as shown and described.

DESCRIPTION

FIG. 1 is an isometric front perspective view of a combined wet/dry vacuum cleaner with tool caddy and wheels showing our design;

FIG. 2 is a front elevational view thereof;

FIG. 3 is a back elevational view thereof;

FIG. 4 is a side view thereof;

FIG. 5 is a side view showing the side opposite that shown in FIG. 4; and,

FIG. 6 is a top plan view thereof.

The electric cord shown in broken lines forms no part of the claimed design.
